DESIGN FOR A BOTTLE

Walter R. Leach, Jr., Chicago, Ill., assignor to Carr-Lowrey Glass Co., Baltimore, Md.

Application September 16, 1937, Serial No. 71,650

Term of patent 14 years

To all whom it may concern:

Be it known that I, Walter R. Leach, Jr., a citizen of the United States, residing at Chicago, in the county of Cook and State of Illinois, have invented a new, original, and ornamental Design for a Bottle, of which the following is a specification, reference being had to the accompanying drawing, forming part thereof.

I claim:

The ornamental design for a bottle, as shown.

WALTER R. LEACH, JR.
